(57) **CLAIM**

The ornamental design for microendoscope, as shown and described.

DESCRIPTION

FIG. 1 is a side view of a microendoscope showing my new design;

FIG. 2 is a front view thereof;

FIG. 3 is a rear view thereof;

FIG. 4 is an enlarged perspective view of the area labeled "4" in FIG. 1;

FIG. 5 is a side view of the microendoscope of FIG. 1, wherein the coupling is detached from the endoscope optics; FIG. 6 is an enlarged side view of the coupling detached from the endoscope optics for ease of illustration;

FIG. 7 is a perspective side view thereof;

FIG. 8 is a side view thereof, wherein the distal sleeve is pushed against the main body of the coupling; and,

FIG. 9 is a rear perspective view thereof.

The broken line showing in FIGS. 1-5, 7 and 9 is for illustration purposes only and forms no part of the claimed design.
